BUILDING CONSTRUCTION

Frederick M. Venzie, Philadelphia, Pa., assignor
to Veco Corporation, a corporation of Penn-
sylvania

Application December 19, 1933, Serial No. 703,046

10 Claims. (Cl. 72—46)

My invention relates to building construction and more particularly to a novel form of wall primarily useful for partitioning, although it may be modified and used as a furring wall.

5 Broadly considered, my invention comprises a multiplicity of surfacing units adapted to be connected to studding members positioned between the opposite faces of the units and connected, movably in one direction, with a floor and a ceiling.

10 An object of my invention is to provide a partition which is supported by studs which are free to move in the plane of the wall while the wall is being erected, and which are positioned between the surfaces of surfacing units such as fireproof slabs.

15 A more specific object of my invention is to provide a partition wall composed of units which may be readily attached to and detached from supports contained within their opposing faces.

20 Another object of my invention is to provide a partition wall composed of a multiplicity of preformed units in which the lute previously found necessary is eliminated, for which is substituted a mastic applied to slots formed adjacent portions of the faces and edges of the units.

25 A further object is to provide a novel wall which may be cheaply and easily erected from preshaped parts.

30 Other and more specific objects and advantages of my invention will be apparent from the following specification, claims, and from the drawing, in which:

35 Fig. 1, is a front elevation of a wall embodying my invention with certain portions broken away to show the parts therebehind;

Fig. 2, is a vertical section of the wall shown in Fig. 1 taken on the lines 2—2 of Fig. 3;

40 Fig. 3, is a horizontal section taken on the lines 3—3 of Fig. 2;

Fig. 4, is a detail perspective view of a clip embodying my invention; and

45 Fig. 5, is a horizontal section of a modified form of my invention.

50 Referring now particularly to the embodiment of my invention shown in the first four figures of the drawing, nailing strips N, preferably of wood, are suitably connected to a ceiling C and floor F of a room in vertical alignment to form a base for the reception of clips 6 (Fig. 4) which are connected to the strips N as by the nails 7 passing through openings 6a in the web 6b of the clip. The clip is preferably formed with two flanges 6c extending in a plane at right angles 55 to the plane of the web 6b, which flanges are

spaced apart a distance equal to the width of a channel 8 extending between opposed clips on the ceiling and floor 8. The channel 8 may be slid into position between the flanges 6c of the clip and with the clips in vertical alignment as shown in Fig. 2 the channel will be held against movement except lengthwise of the clip in the plane of the wall.

5 Preferably a course of fireproof surfacing units 9 is erected, rods 10 passed therethrough, a channel member 8 erected over the rod 10 and then a nut 11 tightened on the rod 10 to force the channel member into a groove 9a in the unit and successive courses of the surfacing units and channels thereafter erected. Various means may 10 be used for holding the first stud in the wall in fixed position, such for instance as that disclosed in my co-pending application for U. S. patent Serial No. 689,579, but since this forms no part of the present invention it will not be described. Obviously, however, each of the vertical rows of 15 units and studs are forced against the end stud, corner post, or door frame, and each other by the nuts 11 on the rods 10 so that further movement of the studs and units in the plane of the 20 wall is prohibited. At the same time the flanges 6c on the clip 6 stop movement of the channels 25 8 out of the plane of the wall.

The surfacing units 9 may be formed with 30 tongues 9b on an edge opposite to the edge carrying a groove 9a, the tongue being adapted to fit within the groove but of less height than the depth of the groove, as will be obvious from a 35 consideration of Fig. 3, and both tongue and groove presenting in cross section the appearance of a section of truncated cone. Thus, when one unit is tightened against an adjacent unit the tongue will be wedged into the groove but a space remains therein through which passes the channel 8. Each of the units 9 may carry in their faces, 40 adjacent the tongues or grooves, slots 9d spaced, preferably, from the portions of the blocks through which pass the rods 10, and preferably extending into the unit a distance less than the 45 distance between the tongue or the groove and the faces of the units so that the slot, adjacent the grooved portion of the unit, does not break the wall of the groove. The slots are so positioned that they correspond when the units are erected and form a cavity into which may be inserted 50 a mastic 20 for increasing the rigidity and fire-proof qualities of the assembled units.

55 While I have herein illustrated my invention as embodying fireproof slabs covered with plaster P to present a finished appearance, it will be obvious

that other types of fireproof units may be used provided they are formed to permit the passage, when erected, of studs between their abutting edges. As illustrated in Fig. 6, instead of a single channel a double channel 15-16 may be used, thus forming an I-beam which may be erected in identically the same manner as the channels 8. In this construction the tongue and groove connection of the fireproof slab previously described is eliminated. The slab is formed with metal faces 17 which are bent over the edges of the slab and formed with tongues and grooves thereon as indicated at 19. In this embodiment of my invention the need for plaster finish is eliminated and a finished coat of paint applied directly to the metal 17.

Various modifications may be made in the above described embodiments of my invention without departing from the spirit and scope 20 thereof as set forth in the following claims.

What is claimed as my invention is:

1. A building construction comprising a ceiling and floor, a multiplicity of positioning members connected to said ceiling and floor, a multiplicity 25 of surfacing units having tongues and grooves on at least two edges, the tongue of one unit and the groove of an adjacent unit being in abutting relationship and said members being positioned therebetween.

2. A building construction comprising a ceiling and floor, a multiplicity of surfacing units having tongues and grooves on at least two edges, said 30 tongues being of less height than the depth of said grooves whereby a space is formed between a portion of said tongue and said groove when said tongues and grooves are interlocked, a multiplicity of positioning members connected to said ceiling and floor and passing through the space between said tongue and groove, and means for maintaining 35 each unit in abutting relationship with a positioning member and with an adjacent unit.

3. In a building construction, a ceiling and floor; nailing strips connected to said ceiling and floor in vertical alignment; a plurality of 45 clips fixed to said nailing strip, each pair of said clips being in vertical alignment; a channel iron maintained in vertical position by each pair of said clips; fireproof slabs; and means for maintaining an edge of a fireproof slab in abutting 50 relationship with said channel iron, said slab being positioned to enclose said channel iron and formed with tongues and grooves thereon.

4. In a building construction comprising a ceiling and a floor; a multiplicity of clips connected to said ceiling and floor, each pair of said 55 clips being in vertical alignment; a metal stud maintained in vertical position by each pair of said clips; fireproof slabs; and means for maintaining an edge of each fireproof slab in abutting relationship with one of said studs, said slabs being positioned to enclose said studs and formed with tongues and grooves thereon.

5. In a building construction a ceiling and a

floor; a plurality of clips fixed to said ceiling and floor; a stud maintained in a vertical plane by said clips; fireproof slabs; and means for connecting an edge of each fireproof slab to a stud, said slab being positioned to enclose said stud and formed with tongues and grooves thereon. 5

6. A building construction comprising a ceiling and floor; a multiplicity of surfacing units having tongues and grooves on at least two edges, said 10 tongues being of less height than the depth of said grooves whereby a space is formed between a portion of said tongue and said groove when said tongues and grooves are in interlocking position; a multiplicity of positioning members connected to said ceiling and floor, each passing 15 through the space between said tongue and groove; and rods passing through said units and members for maintaining each unit in abutting relationship with a positioning member and with an adjacent unit. 20

7. A building construction comprising a ceiling and floor; a multiplicity of surfacing units having tongues and grooves on at least two edges, said 25 tongues being of less height than the depth of said grooves whereby a space is formed between a portion of said tongue and said groove when said tongues and grooves are in interlocking position; a positioning member connected to said ceiling and floor and passing through the space between said tongue and groove, and means for 30 maintaining a unit in abutting relationship with said positioning member.

8. A building construction comprising a ceiling and floor; a multiplicity of surfacing units having tongues and grooves on at least two edges, said 35 tongues being of less height than the depth of said grooves whereby a space is formed between a portion of said tongue and said groove when said tongues and grooves are in interlocking position; a multiplicity of positioning members connected to said ceiling and floor and passing 40 through the space between said tongue and groove; and means for maintaining each unit in abutting relationship with a positioning member and with an adjacent unit. 45

9. In a building construction, a ceiling and a floor; a multiplicity of studs; means for positioning said studs in a vertical position while permitting movement thereof in a single vertical plane, a multiplicity of surfacing units; and 50 means passing through said units and said studs for positioning said units with respect to said studs and each of said studs with respect to the others.

10. A building construction comprising a ceiling and floor, a multiplicity of surfacing units lying in a single plane, a multiplicity of positioning members each movably connected to said ceiling and floor and each positioned between adjacent edges of said surfacing units, and means for 60 connecting said surfacing units to each other and to said members. 55
